UNITED STATES PATENT OFFICE

ODIE OSON COLLINS, OF RIVERSIDE, CALIFORNIA

FUEL PUMP

Application filed April 17, 1930. Serial No. 445,158.

This invention relates to fuel pumps, and has for an object the provision of a novel type of fuel pump, the operation of which is dependent upon the maintenance of a predetermined pressure in the lubricating system of the engine with which the fuel pump is associated, thereby insuring cessation of the operation of the engine should failure of the oil pressure occur through any cause.

10 Another object is to provide simple and efficient means for automatically and quickly priming the pump in the event that the source of supply thereto has been permitted to become dry.

15 Another object is to provide a fuel pump in which the pumping element is in the form of a diaphragm having means associated therewith for reciprocating the center portion thereof, with respect to the plane of 20 its periphery, and in which the reciprocating means are so arranged that the reciprocation of the center portion of the diaphragm extends to equal distances upon opposite sides of that plane.

25 A further object is to provide positive means for easily determining the development of any leak in the reciprocable diaphragm.

This invention possesses other objects and 30 advantageous features, some of which, with those enumerated, will be set forth in the following description of the invention's particular embodiment which is illustrated in the drawings accompanying and forming a part 35 of the specification.

Referring to the drawings:

Figure 1 is a top plan view of a fuel pump embodying the principles of the present invention.

40 Fig. 2 is a longitudinal, vertical, medial sectional view.

Fig. 3 is a horizontal sectional view of that portion of the housing which contains the pumping mechanism. The plane of section is indicated by the line 3-3 of Fig. 2, and the direction of view by the arrows.

The fuel pump of the present invention, is designed primarily for use in conjunction with an internal combustion motor such as 50 that commonly employed for the propulsion

of an automotive vehicle. I wish it to be understood however, that the device is equally susceptible to employment for the purpose of supplying fuel to substantially any type of engine using liquid fuel.

The preferred embodiment of my improved fuel pump, comprises a housing 6 adapted to be secured in any convenient manner such as by a plurality of cap screws 7, to any convenient portion of the base 8 of the motor 55 with which the fuel pump is associated. A preferably circular boss 9 on a side of the housing 6, is adapted to seat within a complementary recess 11 in the motor base 8, so as to hold an aperture 12 in that side of the 60 housing 6 in register with an aperture 13 in the motor base, so as to permit a rocker arm 14 to extend from the interior of the housing 6, into the interior of the motor base, and establish suitable connection with a cam 16 65 which is carried by a cam shaft 17 or any other suitable cyclically-moving part of the motor, so as to effect periodic reciprocation of the rocker arm 14.

The rocker arm 14 is pivotally mounted 70 upon a preferably horizontally extending stub shaft 18 which extends transversely of the aperture 12, and which is preferably rigid with the housing 6. A short arm 19 of the rocker arm 14, extends beyond the stub shaft 75 18 and carries a transversely extending bar 21 and a finger 22 extending downwards to be engaged by a cap or ferrule 23 which is continually urged upwards by means of a coil spring 24 which is retained in axial alignment 80 with the finger 22, by means of a central boss 26 rigid with the bottom 27 of the housing 6. Due to the presence of this spring 24, the finger 22 and arm 19 of the rocker arm 14, are continually urged upwards; with the result 85 that the opposite end 28 of the rocker arm 14, is at all times maintained in riding contact with the cam 16.

Also pivotally mounted upon the stub shaft 18, is a crank arm 31. That end 32 of the 90 crank arm 31, which is pivoted upon the shaft 18, is bifurcated (see Fig. 3) and the only connection between the crank arm 31 and the rocker arm 14, is through the expedient of the bar 21 which engages the upper 95 100

surface of the bifurcated end 32 of the crank arm 31. Hence, movement of the bar 21 downwards, causes corresponding downward pivotal movement of the crank arm 31; but upward retraction of the bar 21 does not cause the return stroke of the crank arm 31. Instead, upward movement of the crank arm 31 is dependent upon a coil spring 33 which is interposed between a cap or ferrule 34 and the upper side of a piston 36. The cap 34 engages a finger 37 at the bottom end of a reciprocably mounted rod 38 to which the outer end of the crank arm 31 is joined. Any convenient means may be employed for joining the crank arm 31 to the rod 38—for example, the outer end 39 of the crank arm 31 may also be bifurcated to engage upon opposite sides of the rod 38 and to permit a pin 41 to extend through the bifurcated end 39 and through a suitable aperture in the rod 38. In view of the rotary motion of the crank arm 31 during reciprocation thereof, it will be necessary when such connecting means are employed, to enlarge laterally the aperture in the rod 38 and/or the apertures in the bifurcated end 39 of the crank arm 31, to permit that amount of lateral movement of the end 39 of the crank arm 31 with respect to the rod 38 which is coincident with the reciprocation of these two elements.

The piston 36 upon which the spring 33 is supported, forms the upper wall of a pressure chamber 46 which is formed in the bottom 27 of the housing 6. A suitable conduit 47 leads from the inlet 48 of the chamber 46, to the pressure lubricating system of the engine with which the pump is associated; and the parts are so proportioned and arranged that the piston 36 is adapted to be forced upwards by oil 49 within the chamber 46 when the pressure of the oil in the lubricating system is maintained at a predetermined value. Upward movement of the piston 36 is limited by means of a ferrule 51 threaded onto the upper end of an annular extension 52 of the side walls of the pressure chamber 46. I prefer to employ some suitable type of sealing means such as a piston ring 53 to establish a substantially leak-proof seal between the piston 36 and the bore of the chamber 46, although no serious consequences will result from a limited amount of leakage of oil from the chamber 46 into the interior of the housing 6 of the pump, inasmuch as any oil which does reach the interior of the housing 6, may find its way through the apertures 12 and 13, into the crank case of the motor.

Within a head 56 which is removably attached to the upper end of the chamber 6 through the expedient of a plurality of cap screws 57 or their equivalent, a pump chamber 58 is formed. A diaphragm 59 extends transversely of the chamber 58, being retained in operative position by having the periphery thereof, compressed between

the head 56 and the upper end of the chamber 6. The center portion of the diaphragm 59 is engaged between opposed plates 61 and 62 which are rigidly connected with the upper end of the rod 38 through the expedient of a nut 63 or its equivalent. Hence, reciprocation of the rod 38 produces corresponding reciprocation of the center portion of the diaphragm 59; and in order to provide guiding means for the reciprocation of these parts, the rod 38 is slidably retained within a cylindrical guide 64 extending downwards from the top of the housing 6.

A bleeder hole 66 establishes communication between the exterior of the housing 6 and the chamber 58 below the diaphragm 59.

The outlet from the pump chamber 58 is by way of a conduit 67 which leads to the carburetor of the engine, or to whatever means for utilizing fuel, are employed. This conduit 67 is connected by means of a conventional union fitting 68, to a valve chamber 69 above a valve plate 71 which is pressed downward upon its seat 72, by means of a spring 73 which is under compression between the valve plate 71 and a plug 74 which is threaded into the upper end of the valve chamber 69. Below the valve plate 71 the valve chamber 69 enters the pump chamber 58 above the diaphragm 59, i. e., upon the opposite side thereof from that with which the bleeder hole 66 communicates.

A lateral extension 76 of the head 56, supports a supply reservoir 77 which preferably serves as a sediment trap. A bail 78 pivotally joined to the extension 76, extends around the bottom end of the trap 77 and carries a threaded pin 79 upon which a thumb nut 81 is threaded. This nut 81 may be screwed upwards against the bottom of the trap 77, to press the trap upwards against a gasket 82 to establish a tight seal between the upper end of the trap 77 and the under face of the extension 76 of the head 56.

Communication is established between the trap 77 and the pump chamber 58 through the expedient of a passage 83 and a second valve chamber 84. The passage 83 enters the chamber 84 above a valve plate 86 which is pressed downwards against its seat 87 by means of a spring 88 which is under compression between the valve plate 86 and a valve plug 89 which is threaded into the upper end of the valve chamber 84. Below the valve plate 86 a draught-tube 91 is threaded into the valve seat 87, this draught-tube 91 extending downwards into the trap 77 and preferably being provided at its lower end, with a strainer 92.

The inlet to the sediment trap 77 is by way of a conduit 96 which leads from the gasoline-tank or whatever source of liquid fuel is employed, and is connected to the extension 76 of the head 56, by means of a

conventional union fitting 97. The entrance 98 of the fitting 97 into the extension 76, communicates with the interior of the trap 77 preferably by means of a tube 99 which extends downwards therefrom a material distance into the trap 77.

Means are also provided for priming the fuel pump. A conduit 101 leading from any suitable area of relatively low pressure, such 10 for example, as the intake manifold of the engine with which the fuel pump is associated, is connected by means of a union fitting 102 to a passage 103 in the extension 76. This passage 103 communicates with a 15 preferably removable valve seat 104 having a relatively small aperture 106 extending therethrough into the passage 103. A needle valve 107 is associated with the valve seat 104, and is rigidly connected to a float 108 which is disposed inside the trap 77 adjacent the upper end thereof. Preferably the 20 tubes 91 and 99 serve as guides limiting the movement of the float 108 and needle valve 107, to vertical movement; and a stop 109 25 is provided upon one or both of the tubes 91 and/or 99, to limit downward movement of the float 108, and thus prevent complete withdrawal of the needle valve 107 from the seat 104.

30 It should be pointed out that the parts are so proportioned and arranged that the reciprocation of the rod 38, movement of which in one direction is caused by the downward movement of the arm 31 coincident with 35 rotation of the cam 16 against the end 28 of the rocker arm 14, and the return stroke of which is caused by the spring 33, causes the center portion of the diaphragm 59 to move the same distance above the plane of the periphery of the diaphragm upon the upstroke, 40 as the distance below that plane which this portion of the diaphragm moves upon the downstroke thereof. In this manner, the maximum stroke of the center portion of the 45 diaphragm, is attained with a minimum amount of distortion thereof from true planar arrangement, as compared with the more usual manner of utilizing a diaphragm pumping member wherein the diaphragm at 50 one end of its stroke, lies substantially flat, and at the other end of its stroke is distorted to permit the center portion of the diaphragm to lie in a plane spaced from the plane of the periphery, a distance equal to the maximum 55 stroke. The full line position of the diaphragm 59 upon Fig. 2, indicates the position of the diaphragm when at substantially the bottom of its stroke, whereas the dashed line position indicated at 59', shows substantially 60 the position of the diaphragm when at the upper extreme of its stroke.

Operation

If, for any reason, the sediment trap 77 65 has been emptied, it will automatically be

filled or "primed" as soon as the crankshaft of the engine starts to turn, because of the vacuum developed in the intake manifold by the pumping action of the pistons of that engine. Inasmuch as the conduit 101 70 communicates with the intake manifold or some other part of the mechanism wherein an area of low pressure exists, under such circumstances, air will be drawn past the needle valve 107 and through the conduit 101. 75 However, the only inlet to the sediment trap 77, is through the conduit 96 which leads from the gasoline-tank because the spring-pressed valve plate 86 precludes the possibility of entrance into the sediment trap 77 by way of the passage 83. Accordingly, gasoline or whatever liquid fuel is being employed, will be drawn through the conduit 96 and into the sediment trap 77. This flow of fuel into the trap 77 will continue, provided rotation of the crankshaft is continued, until the level of the liquid within the trap 77 has reached that height which results in floating the float 108 sufficiently to bring the valve 107 80 into seating engagement with the valve seat 104. This is the normal position of the valve 107 and float 108, it being understood that these parts become displaced from this position only when the liquid within the trap 77 85 has fallen below a predetermined level.

In this manner, a sufficient quantity of liquid fuel is automatically maintained within the trap 77, so that the lower end of the draught-tube 91, is immersed therein. Consequently, the downstroke of the diaphragm 59, will cause a given quantity of this fuel to be drawn past the check valve 86, through the passage 83, and into that portion of the pump chamber 58 which is above the diaphragm 59. As soon as the downstroke of the diaphragm ceases, the check valve 86 will be seated by its spring 88; with the result that the upstroke of the diaphragm 59, causes the ejection of the same amount of fuel as that which was previously drawn into the chamber, this ejection occurring however, past the check valve 71, and thence into the fuel line 67. The parts are so proportioned and arranged that the length of the stroke of the diaphragm, is just sufficient to supply 100 the maximum amount of fuel which will be necessary for the satisfactory operation of the motor under any circumstances.

As will readily be understood, reciprocation of the diaphragm 59, occurs as a result 105 of rotation of the cam shaft 17. Accordingly, this reciprocation of the diaphragm, occurs at all times that the crankshaft of the motor is rotating, inasmuch as there is a suitable interconnection (not shown) between the crankshaft and the cam shaft 17. The engagement of the end 28 of the rocker arm 14 with the cam 16, causes lateral reciprocation of the end 28 and vertical reciprocation 110 of the short arm 19, and with it the bar 21. 115

Inasmuch as the bar 21 rests upon the upper face of a portion of the crank arm 31, downward movement of the bar 21, will cause similar downward movement of the crank arm 31, resulting in drawing the center portion of the diaphragm 51, downwards. As soon as the crest of the cam 16 has passed its line of contact with the rocker arm 14, elevation of the bar 21 will commence, with the result that the spring 33 will then cause the return stroke of the rod 38 and the center portion of the diaphragm 59; provided a sufficient pressure is imposed upon the oil 49 within the chamber 46, to retain the piston 36 at its position of maximum elevation against the counter-thrust of the spring 33. In the event that the pressure lubricating system of the engine has failed from any cause, the pressure imposed upon the oil 49 within the chamber 46, will be relieved, permitting the piston 36 to drop, whereupon the spring 33 will be unable to push the rod 38 upwards to cause the return stroke of the diaphragm. Consequently, the supply of fuel to the motor, is dependent upon the existence of a predetermined pressure upon the oil 49 within the chamber 46; and whenever such pressure fails, the motor will automatically be stopped through the failure of the delivery of a sufficient quantity of fuel to the carburetor.

It is to be understood that the details of the invention as herein disclosed, are subject to alteration within the spirit or scope of the appended claims.

35 I claim:

1. In a fuel pump, a pumping member operable by reciprocation thereof, means for periodically moving said pumping member in one direction, a pressure chamber adapted to receive fluid under pressure, a wall of said chamber being movable and responsive to variation of pressure therebehind, and means supported on said movable wall for moving said member in the other direction.
- 40 2. In a fuel pump, a pumping member operable by reciprocation thereof, a pressure chamber, means connecting said chamber to a pressure lubricating system, a wall of said chamber being movable with respect to the remainder of said chamber and responsive to pressure changes therein, spring means interposed between said movable wall and said pumping member for moving the pumping member in one direction, and means for periodically withdrawing said pumping member against the action of said spring means.
- 45 3. In combination with an internal combustion engine having a fuel intake and a pressure lubricating system; pumping means, a conduit connecting said pumping means with said fuel intake, a pressure chamber, means connecting said pressure chamber to said lubricating system, and means dependent upon the maintenance of a predetermined

pressure within said chamber for actuating said pumping means.

4. In combination with an internal combustion engine having a fuel intake and a pressure lubricating system, reciprocable pumping means, a pressure chamber, means connecting said chamber to said lubricating system, a wall of said chamber being movable with respect to the remainder of said chamber and responsive to pressure changes therein, spring means interposed between said movable wall and said pumping means, and means actuated by a cyclically-moving part of said engine for withdrawing said pumping means against the action of said spring means. 75 80

5. In combination with an internal combustion engine having a fuel intake and a pressure lubricating system, reciprocable pumping means, a pressure chamber, means connecting said chamber to said lubricating system, a piston reciprocable in said chamber, spring means interposed between said piston and said pumping means, and means actuated by a cyclically-moving part of said engine for withdrawing said pumping means against the action of said spring means. 85 90

6. In a fuel pump a housing having a chamber, a diaphragm extending thereacross, valved inlet and outlet passages communicating with said chamber on one side of said diaphragm, a rod rigid with said diaphragm, said housing having a pressure chamber therein, means connecting said pressure chamber to a source of fluid under pressure, a piston reciprocable within said pressure chamber, a spring interposed between said piston and said rod, and means for periodically moving said rod against the action of said spring. 95 100

7. In a fuel pump a housing having a chamber, a diaphragm extending thereacross, valved inlet and outlet passages communicating with said chamber on one side of said diaphragm, and means for reciprocating the center portion of said diaphragm in a direction perpendicular to the normal plane thereof, the stroke of said center portion extending to equal distances upon the opposite sides of the plane of the periphery of the diaphragm. 105 110

8. In a fuel pump a housing having a chamber, a diaphragm extending thereacross, valved inlet and outlet passages communicating with said chamber on one side of said diaphragm, and means for reciprocating the center portion of said diaphragm, said housing having a bleeder hole extending from the exterior thereof to said chamber on the other side of said diaphragm. 115 120

9. In a fuel pump, pumping means, a sediment trap, a passage leading from said sediment trap to said pumping means, a conduit leading from said trap to a source of liquid fuel, and means for automatically priming said sediment trap to draw sufficient fuel thereinto to fill the trap above the level of the entrance thereinto of said passage. 125 130

10. In a fuel pump, pumping means, a sediment trap, a passage leading from said sediment trap to said pumping means, a conduit leading from said trap to a source of liquid
5 fuel, a valve seat in the top of said trap, a valve associated therewith, a float connected to said valve and adapted to close the valve when the level of the fuel within said trap reaches a predetermined height, and a conduit leading from said valve seat to an area of relatively low pressure.
11. In a fuel pump, a pumping member operable by reciprocation thereof, means for periodically moving said member in one direction, a pressure chamber adapted to receive fluid under pressure, and means operated by pressure within said chamber for moving said pumping means in the other direction.
- 15 12. In a fuel pump, a pumping member operable by reciprocation thereof, means for periodically moving said member in one direction, a pressure chamber adapted to receive fluid under pressure, means operated by pressure within said chamber for moving said pumping means in the other direction, and resilient means interposed between said pressure-operated means and said pumping member to permit movement of said pumping
20 member by said periodically moving means against the action of said pressure-operated means.
- 25 13. In combination with an internal combustion engine having an intake manifold, a carburetor, and a fuel supply conduit, pumping means, a supply reservoir communicating with said pumping means and with said conduit, a valve seat in the top of said reservoir, a valve associated therewith, a float connected
30 to said valve and adapted to close the valve when the level of the fuel within said reservoir reaches a predetermined height, and a conduit leading from said valve seat to said manifold.
- 35 45. In testimony whereof I have signed my name to this specification.

ODIE OSON COLLINS.
